UNITED STATES PATENT OFFICE

ROY J. DAVIS AND GEORGE E. WATTS, OF PORTLAND, OREGON

AEROPLANE HATCH COAMING

Application filed June 13, 1931. Serial No. 544,160.

Our invention relates to coamings fitted about the aperture in the fuselage through which access is had to the cockpit, the same serving as a fending and resilient padding sheathing the marginal edge of the fuselage structure, and particularly to a special composition and form thereof of desirable aerodynamic characteristics adaptable universally to the varying figures and curves of the openings of the several models.

The principal object of our invention is to provide a standard coaming having all of the desirable characteristics of such a fitting in an enhanced degree capable of quick and easy attachment.

A second object is to provide for an enhanced durability of the coaming.

A third object is to facilitate the manufacture of the coaming and hence provide for an improved quality and lesser cost.

Other objects and advantages of our invention will be apparent in the following discourse wherein the significance of the reference characters in the accompanying drawings, details of construction of a typical coaming embodying our invention, and the particular advantages thereof are explained.

Figure 1 represents a view of the side of a fragment of an aeroplane fuselage fitted with the hatch coaming of my invention.

Figure 2 represents a view of a transverse section of the coaming as manufactured.

Figure 3 represents a view of a length of the coaming as manufactured.

Figure 4 is a diagram representative of the cross-sectional figure of the coaming when applied to the fuselage, a fragment of the latter being shown in section.

Figure 5 is a diagram illustrative of certain effects described further on.

Our invention consists in the particular form and combination of materials of a standard design and construction adapted for manufacture in continuous lengths.

The coaming is composed of a continuous length of resilient material as sponge-rubber of the uniform sectional form illustrated in Figure 2 where the sponge-rubber body is indicated by the numeral 1. The sponge-rubber body is encased in an adhering fabric

covering 2, the edges of which are disposed within the tapered groove A of the form shown. As manufactured, a length of the coaming is straight as shown in Figure 3.

Upon application to the fuselage involving the bending of the coaming to conform to the curves of the edge covered, the normal cross-sectional figure of the coaming as illustrated in Figure 2 is distorted to that form illustrated in Figure 4 where it will be observed that the groove is of rectangular section. A virtually perfect adaptation of the coaming to the fuselage is thus effected.

In detail this adaptation accrues out of the following properties of the materials employed as related to the effects of distorting the normally straight length of coaming with a normally tapering groove to the irregularly curved figure of the fuselage edge:

The fabric covering 2 is susceptible of great compression in its linear dimensions and of relatively little extension thereof. The sponge-rubber body is possessed of a modified hydraulicity as well as resilience. In accordance with the laws governing bending strains, the sponge-rubber body of the coaming tends to bend about a neutral axis disposed medially of its cross-sectional extremities as determined by the moments involved, and in natural course that portion lying nearest the center of curvature will be compressed and that portion most remotely situated therefrom will be strained in tension.

In bodies of symmetrical section these strains are productive of forces tending to distort the cross-sectional figure of the body in a manner to decrease that dimension thereof measured in the plane of curvature and to increase that dimension perpendicular thereto. But in the coaming of my invention the compressive strains in that portion lying nearest the center of curvature are communicated to the portions most remote therefrom, and, since the tapered groove provides a void in this latter portion, these strains are resolved into forces and hence movements thereof effecting the narrowing of the groove.

It will be quite apparent that after the void

provided by the groove is filled either by the movement of the groove walls toward each other or by the fuselage structure, or the combination or both, further strains will 5 tend to distort the coaming so as to increase the dimension thereof perpendicular to the plane of curvature. Now, such further straining is contemplated in my invention to provide for a liberal range of variation 10 in degrees of curvature of the edge of any fuselage or of a great variety of models of aeroplanes or style of hatchway; the dimension measured perpendicularly to the plane of curvature at any point not being critical. 15 It will also be apparent that any compression of the length of the coaming will be reflected in strains tending to force the extreme lips of the coaming into closer contact with the fuselage structure. Such compression in length is practicable in the application of the coaming and facilitates the making of butt joints. This is in distinct 20 contrast to the method of drawing a covering material over a stuffing and securing the former to the fuselage structure at intervals. In the coaming of my invention the edges of the lips are forced into contact with the fuselage structure at every point regardless 25 of the manner of securing the same thereupon, thus providing a fair and smooth surface of improved aerodynamic characteristics.

The fabric covering provides further effects contributing to the total mechanical effects thus produced as well as affording a surface adapted to finishing in any desired manner. The warp of the fabric is disposed 30 parallel with the length of the coaming in its manufacture, providing for the disposition of the transverse yarns in a manner to be strained in tension during the distortion of the coaming to fit the particular fuselage to which it is attached. Thus, since the figure of the section is approximately circular 35 in one part, the compression of the sponge-rubber body will be adequately contained and the pressure so developed in bending will be communicated to the extended portions. On 40 the other hand the warp yarns disposed at the greatest radius from the center of curvature will tend to constrain the lips of the coaming into close contact with the fuselage in view of the location of the center of resistance of the sponge-rubber body to this 45 centripetal action of these yarns strained in tension.

In addition to these effects the fabric covering provides for the convenient riveting of the coaming to the fuselage structure, as 50 indicated at 3 in Figure 4, to insure against accidental displacement.

In the course of time after the coaming of our invention is applied to the aeroplane it 55 assumes a permanent set and the strains are more or less equalized so that eventually, a

coaming thus applied becomes ideally adapted to the figure of the fuselage edges.

The advantages of the coaming of our invention will be readily apparent to the aviator and manufacturer.

Having described our invention what we claim is:

1. The method of forming hatch coaming for aeroplanes consisting in the forming of a length of fabric covered resilient material of such normal uniform cross section as described characterized by a tapered groove and the subsequent bending thereof to conform to the figure of the edge to which it is applied to effect the closure of the said tapered groove to make substantial contact with the fuselage structure.

2. An aeroplane hatch coaming of resilient material and of normally straight form and of uniform cross section characterized by a circular portion and two symmetrical extending lips forming therebetween a normally tapered groove.

3. Aeroplane hatch coaming comprising indeterminate lengths of normally straight resilient material of the uniform cross-sectional figure characterized by a circular portion and extended lips embracing a tapered groove.

4. Aeroplane hatch coaming in indeterminate lengths of normally straight form, resilient composition, and the uniform cross-sectional figure characterized by a circular portion and extended lips embracing a normally tapered groove adapted to engage the fuselage structure when the coaming is bent to the curves of the fuselage edge.

5. Aeroplane hatch coaming consisting of a normally straight resilient body of the uniform cross-sectional figure characterized by a circular portion and extended lips embracing a normally tapered groove adapted to engage the edge of the fuselage structure when bent thereto, the same being covered with adhering fabric whose warp is disposed parallel to the length of the coaming and whose edges are disposed within said normally tapered groove.

6. Aeroplane hatch coaming consisting of normally straight continuous lengths of elastic resilient material of the cross-sectional figure characterized by an approximately circular portion and extended lips embracing a normally tapered groove adapted to engage the edge of the fuselage structure when bent thereto, the same being covered with a fabric whose warp is disposed parallel to the length of the coaming and whose edges are disposed within said normally tapered groove.

ROY J. DAVIS.
GEORGE E. WATTS.
